UNITED STATES PATENT OFFICE

PETER RÜTTIMAN, SR., OF SIEBNEN, AND FRITZ HOLZSCHEITER, OF ZURICH, SWITZERLAND, ASSIGNORS TO MASCHINENFABRIK KIESSLING A.-G., OF LEIPZIG, GERMANY

MACHINE FOR SCORING WOODEN BOARDS

Application filed October 13, 1927, Serial No. 226,002, and in Germany October 14, 1926.

The present invention relates to a machine for scoring wooden boards on which veneer is to be applied. The main object of the invention is to provide a machine which is especially adapted to make the very minute scores in the surface of wooden boards which are to be veneered; the scores serving for retaining glue by which the veneer is fastened on the board.

10 A further object of the invention is to provide a machine which will make scores parallel to each other at equal distances apart, and a still further object consists in providing an improved machine so constructed and arranged that two sets of parallel flutes are produced simultaneously thereby and which cross each other, say at a right angle.

With these and other objects in view the invention consists in the construction, combination and arrangement of devices herein-after fully described and particularly pointed out in the claims.

In the accompanying drawings the machine is shown in a diagrammatical manner.

25 Fig. 1 is a side elevation of the machine,

Fig. 2 is a top view,

Fig. 3 is a vertical section on line A—B of Fig. 2,

Fig. 4 illustrates the motor with part of the 30 driving gear,

Fig. 5 shows a section on line C—D of Fig. 8,

Fig. 6 is a side elevation of a part of the chain carrying the scoring tools,

35 Fig. 7 is a top view thereof,

Fig. 8 shows the mounting of the tool-chain on a driving gear,

Fig. 9 is a cross-section through a tool,

40 Fig. 10 shows a knife and Fig. 11 a scored board.

In the drawings 1 denotes the frame of the machine, 2 is a table adjustably mounted in said frame 1. The table 2 rests on two supports 3, 4 which are supported by wedges 5, 6 45 movably arranged in guide grooves of the frame 1 of the machine. The table 2 may be adjusted in vertical direction by moving said wedges 5, 6, the table 2 being secured by guide pieces 7, 8 against lateral displacement. In 50 the two supports 3, 4 two rollers 10, 11 are ro-

tatably mounted over which the endless band 9 runs. The band 9 is preferably of rubber, and passes over supporting ledges arranged in a central opening of the table 2 and serves to forward the board to be worked beneath 55 the tools as described hereinafter. The roller 10 is driven by a chain 13 (which is indicated in dotted lines in Fig. 1) which runs over a chain wheel 12 fixed to the shaft of the roller 10 and over a chain wheel 14 fixed to 60 an intermediate shaft 17 journalled in the frame 1 of the machine. The shaft 17 is driven from a wheel 16 by means of a chain 15 (which is shown in dotted lines in Fig. 1), the wheel 16 being keyed on a shaft 17^a. The 65 shaft 17 is driven by a motor 18 by means of two spur wheels 20, and a speed reduction gear 21. The wedges 5, 6 are adjusted by screw threaded spindles 22, 23, rotatably mounted in the frame 1 and screwed into the 70 wedges 5, 6. To rotate the spindles 22, 23 a suitable gearing 25 of known construction is provided (which is indicated in dotted lines in Fig. 1) which is driven by a crank etc.

Above the table 2 and the horizontal portion of the band 9, two endless chains 26 are arranged extending across the table 2. The chains 26 are positioned parallel to each other and run in opposite directions to each other, and at right angles to the direction in which the band 9 runs (Fig. 2). Each of the chains 26 runs over two chain wheels 28, 29 rotatably arranged in supports 30 rigidly fixed to the bed 1 and driven by means of two helical gears 33, 34, fixed on a shaft 35. The shaft 75 35 which is journalled on top of the supports 30 is driven by a chain 36 from the shaft 17, the chain 36 running over two idle rollers 38, 39 and over a chain gear 40 on shaft 35. The helical gears 33, 34 respectively drive the 80 shafts 41, 41^a of the sprocket wheels 28, 29 by helical gears 42, 43 with which said shafts 41, 41^a are provided. The wheels 28, 29 and therewith the chains 26 run in opposite directions to each other, and each is provided with 85 two toothed flanges (Fig. 5).

Each chain 26 comprises an equal number (Fig. 5) of link plates 50 which are arranged in spaced relation and are connected together by links 51 and bolts 52 100

(Fig. 7). On each plate 50 four rollers 53 are rotatably mounted, the rollers 53 engaging grooves 54 (Fig. 8) in the supports 30. Said grooves 54 run parallel with the upper lead of the band 9 and the rollers 53 engage the grooves 54 with practically no backlash. On each plate 50 a shoe 55 is slidably mounted on bolts 57. The front portion is slightly bent-off at 56 to facilitate the gliding of the shoe on the wooden board B constituting the work (Fig. 8). A spring 58 coiled around on a bolt 57 abutting on plate 50 and shoe 55 tends to press the shoe 55 downwards and keeps the shoe in close contact with the surface of the board B to be scored. On each shoe a knife 58 is removably held by screw bolts. The working edge of the knife 58 is serrated, the teeth 59 being close to each other, and the distance between two adjacent teeth is about 1 to 3 mm. The teeth 59 protrude slightly beyond the lower gliding face of the shoe 55. The knife 58 and the edge 56 run at an angle of 45° to the line of travel of the chain. In the path of the knives 58 project rotating brushes 60 which brush off the chips taken off the board B by the teeth 59. The brushes 60 are driven from the shaft 35 by means of helical gears 61, 62, and sprocket wheels 63 and chains 64. Balls 70 housed at the ends of the bolts 52 are adjustably mounted, run on the walls of the guide grooves 54 and prevent lateral play of the chains.

To press the board B on to the rubber band 9 four rollers 65 are provided. The rollers 65 are covered with a mantle of rubber and are journaled in blocks 67 movable against the action of springs 66 in vertical slots on the support 30.

The speed of the band 9 and therefore the speed of the board B carried by said band 9 beneath the rollers 65 and the tool chains 28, 29 is equal to the speed of said tool chains 28, 29. The teeth 59 of the knives 58 cut shallow grooves C scores or flutes in the upper face of the board B. Said scores or scratches may run at 45° to the direction in which the board is moved by the band and the scores produced by the one tool chain 28 cross the scores produced by the other chain 29 at 90° (Fig. 11) as the two chains run in opposite directions. The length of the knives 58 and their distance apart is such that the scores produced by one knife are close to those produced by the preceding knife, the distance therebetween being equal to the pitch of the teeth 59.

The means to adjust the table to suit varying thicknesses of boards are well known as well as their operation and need not be described.

What we claim and wish to secure by U. S. Letters Patent is:—

1. In a machine of the class described, the

combination of means to feed the work in one direction, tool carrying means arranged to move a tool across the work in a direction at an angle to that of the movement of the work so that the movement of the tool across the work is diagonal to the movement of the tool and also diagonal to the direction of movement of the work, said tool carrying means being an endless chain comprising plates flexibly connected together and each plate being provided with a shoe to move over the surface of the work and with a tool carried by said plate.

2. A machine as claimed in claim 1, in which the tool carrying means is an endless chain comprising plates flexibly connected together and each plate is provided with a shoe to move over the surface of the work and with a tool carried by said plate, said shoe being movable to some extent toward and from the plate and a spring being provided which is active to move the shoe from the plate to press the shoe and the tool carried thereby against the work.

3. A machine as claimed in claim 1, in which the tool carrying means is an endless chain comprising plates flexibly connected together and each plate is provided with a shoe to move over the surface of the work and with a tool carried by said plate and provided with a serrated edge presented to the work.

In witness whereof we affix our signature.

PETER RÜTTIMAN, SENIOR.
FRITZ HOLZSCHEITER.
